(57) **CLAIM**

The ornamental design for a display panel or screen with a graphical user interface, as shown and described.

DESCRIPTION

FIG. 1 is front view of a display panel or screen with a graphical user interface showing our new design; and, FIG. 2 is a front view of a second embodiment thereof. The broken line showing of a display panel or screen and the graphical elements in both views is for illustrative purposes only and forms no part of the claimed design.
